[57] CLAIM

The ornamental design for a stroller front end, as shown and described.

DESCRIPTION

FIG. 1 is a front perspective view of a front end for a stroller, the stroller being shown in phantom lines and forming no part of this design;

FIG. 2 is a top plan view of the front end;

FIG. 3 is a front elevational view thereof;

FIG. 4 is a right side elevational view thereof, the left side being a mirror image;

FIG. 5 is a rear elevational view thereof;

FIG. 6 is a bottom plan thereof; and,

FIG. 7 is a rear perspective view thereof.
